UNITED STATES PATENT OFFICE.

ALONZO H. GREENE, OF FORT WORTH, TEXAS.

GLAZING MACHINE.

Application filed December 1, 1924. Serial No. 753,206.

To all whom it may concern:

Be it known that I, ALONZO H. GREENE, a citizen of the United States, residing at Fort Worth, in the county of Tarrant and 5 State of Texas, have invented certain new and useful Improvements in Glazing Machines, of which the following is a specification.

My invention relates to glazing machines 10 and more particularly to machines for applying putty and making a smooth finish; and the object is to provide machines for mixing putty and for applying the putty mechanically and in a more practical manner and for doing the work efficiently and 15 which will be more economical. Other objects and advantages will be fully explained in the following description and the invention will be more particularly pointed out in the claims.

Reference is had to the accompanying drawings which form a part of this application.

Fig. 1 is a front elevation of the machine. 25 Fig. 2 is an end elevation of the same. Fig. 3 is a detail view of the nozzle. Fig. 4 is a plan view of the machine. Fig. 5 is a detail view of the clip mechanism for holding the reel temporarily stationary. Fig. 6 30 is a longitudinal section of a safety valve for regulating the flow of the putty. Fig. 7 is a detail view of the pump. Fig. 8 is a longitudinal section of the discharge nozzle of the putty applying nozzle.

Similar characters of reference are used 35 to indicate the same parts throughout the several views.

The machine is provided with an upright frame, having posts 1 and cross-bars 2 at 40 the top part of the frame attached to the uprights 1. A four armed reel is provided with two sash holding arms 3 and two sash bracing arms 4 and the reel is journaled in a bearing 5 which is attached to a post 6. 45 The post 6 is braced by a bar 7 which is attached to the post 6 and to a frame member 2. The reel is to be turned by hand or manually. The arms 3 are provided with spring clips or brackets 8 which are loosely 50 mounted on the arms 3 by means of a collar 9 and held in place by a spring 10 which is attached to a lug projecting from the collar 9 and to a lug which projects from a collar 11 which is rigidly mounted on the arm 3. 55 The collar 9 is made stationary on the arm 3 by a pin or lug which is carried by the

lever 12 and projects through the collar 11 in the reel arm 3. The arm 3 is provided with a number of holes so that the collar 11 can be adjusted to different points on the 60 arm 3. The object is to adapt the brackets for holding sash of different dimensions. The object of the springs 10 is to permit the adjustment of the sash on the reel. The edge of the sash is placed on the lug and 65 pressed downwardly until the sash at the upper side will pass under the lug 8 on the upper part of the reel arm 3 above the bearing 5. It will be understood that the collars 9 and 11 and their attachments are duplicated on each arm 3. During operation the 70 reel is prevented from turning by a spring keeper 13 which is mounted in the post 6 and projects through a casing 14 and is held projected against an arm 3 by a 75 spring 15.

The machine is provided with a hopper 16 for receiving the ingredients for making putty and the putty is mixed in the hopper. A pump 17 is provided and is driven by a 80 motor 18 by suitable gearing. The motor drives a belt 19 which drives a pulley 20 rigid on shaft 21. A loose pulley 22 is mounted on the shaft 21 and a belt shifter 23 is provided for shifting the belt 19. The 85 motor 18 can be started while the belt 19 is on the loose pulley 22 and then shifted to the fast or tight pulley 20 when it is time to start the machine to work. The shaft 21 drives a sprocket wheel 24 which is rigid on 90 shaft 21 and this wheel drives a sprocket chain 25 which drives a sprocket wheel 26 which is rigid with shaft 27. Two sprocket wheels 28 and 29 are mounted on the shaft 27 to give two different speeds and a clutch 95 30 is provided for locking either one of the wheels 28 and 29 to the shaft 27 for driving purposes. A lever 31 is provided for actuating the clutch 30. The wheel 28 drives a sprocket chain 32 and wheel 29 drives a 100 sprocket chain 33. The chain 32 drives a sprocket wheel 34 and chain 33 drives a sprocket wheel 35. The shaft 36 may be driven by either one of the wheels 34 and 35. The object of the provision of two different 105 speeds is to force the putty from the pump 17 at two different speeds. When the putty is to be driven through the larger pipe 37, faster speed is required and the clutch 30 will be thrown in mesh with the clutch of wheel 28 to drive the chain 32. The three-way valve 38 is turned to start the putty through 110

the pipe 37. When the putty is to be forced from the pump through the putty applying hose 39, the clutch 30 is thrown in mesh with the wheel 29 to drive chain 33 which will 5 give a slower speed. The three-way valve 38 will be turned to start the putty through the hose 39. The putty can then be applied to the sash through the hose 39.

Means are provided for regulating the 10 pressure of the putty in passing through the hose 39. A pipe 40 is connected to the pipe 41 which supplies putty to the hose 39. The pipe 40 leads within the hopper 16 and a relief valve is connected to the pipe 40. 15 This valve consists of a tube 42 which is connected to pipe 40 and of casing 43 and of a spring actuated plunger 44 which carries a point 45 adapted to close the passage 46 from the pipe 40 to the tube 44 and to open 20 this passage more or less. The plunger 44 is actuated by a spring 47. In operation, the casing 43 can be screwed more or less on the tube 44 to regulate the tension of the spring 47. If the tension of spring 47 is 25 increased, the point 45 will tend to close the passage 42 and so retard the passage of putty through the pipe 40 and to increase the flow of putty through the hose 39. If the tension of the spring is decreased, the flow 30 of putty through the pipe 40 will be increased and the flow through the hose 39 retarded. In this manner the proper flow through the hose may be regulated to the required flow. If the flow through the hose 35 is stopped by turning the valve 48, all the putty will pass through pipe 40 and the passage 42 and escape through opening 49 into the hopper 16.

The hose 39 is provided with a nozzle 49 40 and a valve 48. A lever 50 is provided for cutting off the flow of putty through the nozzle. Provision is made for handling the hose 39 to make the handling easier for the operator. A crane 51 is pivotally connected to a hollow post or tube 52. A weight 53 is connected to a chain or cable 54 which runs over idlers 55 and 56 and is provided with a hook for engaging the hose 39. The weight 53 moves freely in the post 50 52. The operator can direct the nozzle 49 to the required point without having to carry the weight of the hose. The hose can be supported by the crane and its attachments when the hose is not in use.

55 Various changes in the sizes, proportions, construction and arrangement of the several parts of the invention above described may be made without departing from my invention.

60 What I claim, is,—

1. A glazing machine comprising an up-right frame, a reel and a shaft therefor journaled in said frame, means for mounting a sash on said reel, a hopper and mechanism for mixing ingredients in said hopper

including a pump in communication with said hopper and a pipe communicating with said pump and with said hopper, and gearing for driving said pump.

2. A glazing machine comprising an up-right frame, a reel and a shaft therefor journaled in said frame, means for mounting a sash on said reel, a hopper and mechanism for mixing ingredients in said hopper, and a flexible hose provided with a discharge nozzle for applying the mixed material or putty to the sash on said reel. 75

3. A glazing machine comprising an up-right frame, a reel and a shaft therefor journaled in said frame, means for mounting a sash on said reel, a hopper and means for mixing ingredients in said hopper including a pump, and means for applying putty to a sash on said reel including said pump and a flexible hose operatively connected to said pump and provided with a discharge nozzle. 80

4. A glazing machine comprising an up-right frame, a reel and a shaft therefor journaled in said frame, means for mounting a sash on said reel and means for holding the sash yieldingly on said reel, a hopper and means for mixing material in said hopper including a pump and a pipe for circulating ingredients through the pump and the hopper, and means for applying putty to sash on said reel including said pump and a flexible hose provided with a discharge nozzle. 85

5. A glazing machine having means for supporting sash in position for glazing, a hopper and means for mixing material in said hopper including a pump and a pipe for circulating material through said pump and hopper, means for applying putty to sash including said pump and a flexible hose connected to said pump and provided with a discharge nozzle, and means for varying the speed in moving putty for different purposes and in different quantities. 100

6. A glazing machine having means for supporting sash in position for glazing, a hopper and means for mixing material in said hopper including a pump and a pipe for circulating material through said pump and hopper, means for applying putty to the sash including a pipe connected to said pump and a flexible hose connected to said pipe and provided with a discharge nozzle, and means for regulating the pressure of putty passing through said hose. 105

7. A glazing machine having means for supporting sash in position for glazing, a hopper and means for mixing material in said hopper including a pump and a pipe for circulating material through said pump and hopper, means for applying putty to the sash including a pipe connected to said pump, a flexible hose connected to said pipe, a discharge nozzle provided with a cut-off 110

valve, and a combined pressure regulator for the putty passing through said hose and overflow or relief means for returning putty to said hopper.

- 5 8. A glazing machine having means for supporting sash in position for glazing, means for mixing putty including a hopper and a pump, means for operating the pump, means for applying putty including a flexible hose operatively connected to said pump and provided with a discharge nozzle, and means for supporting said hose and nozzle for use of an operator, including a swinging crane provided with a hook for supporting the hose in different positions for the use of the operator.
- 10
- 15

9. A glazing machine having means for supporting sash in position for glazing, means for mixing putty including a hopper and a pump and a pipe for circulating material through said pump and hopper, means for applying putty to sash including a flexible hose operatively connected to said pump and provided with a discharge nozzle, means for operating said pump at a higher speed when mixing material through said hopper, and means for operating said pump at a lower speed when forcing putty through said hose. 20 25

In testimony whereof, I set my hand, this 30
25th day of November, 1924.

ALONZO H. GREENE.
